UNITED STATES PATENT OFFICE.

LOUIS JACK, OF MOYLAN, PENNSYLVANIA.

ADJUSTABLE FORM FOR SMOKE-CHAMBER CONSTRUCTION FOR CHIMNEYS HAVING OPEN FIREPLACES.

1,021,985.

Specification of Letters Patent. Patented Apr. 2, 1912.

Application filed September 15, 1911. Serial No. 649,588.

To all whom it may concern:

Be it known that I, LOUIS JACK, a citizen of the United States, residing in Moylan, county of Delaware, State of Pennsylvania, 5 have invented a certain new and useful Adjustable Form for Smoke-Chamber Construction for Chimneys Having Open Fire-places, of which the following specifications are a description, reference being had to the 10 accompanying drawings of the said applica-
nace, in which like letters and numerals of reference indicate similar parts in the several views, which form a part of the specifications and also are in demonstration of 15 the mode of applying to use my invention.

The purpose of this appliance is to control and facilitate the constructural form and quality of smoke chambers of chimneys having open fire places. This important 20 part of chimneys made of masonry usually encounters difficulty and uncertainty in the construction to secure form, size, direction and smoothness in order to effectively discharge into the smoke-flue the fumes arising 25 from the combustion of fuel in open fire places. An additional function of the appliance is to support the masonry of the smoke chamber.

Figure 1, is a perspective view of my 30 smoke chamber former. Fig. 2, is a perspective detail thereof. Fig. 3, is a detail of an adjustable tie-bar. Fig. 4, is a sectional front elevation of a fire place with an adjustable smoke chamber former in position 35 therein. Fig. 5, is a side elevation of my smoke chamber former in position. Fig. 6, is a detail of a brace with adjusting perforations. Fig. 7, is a diagrammatic front view showing my smoke chamber former 40 deflected laterally.

Concerning Fig. 1, B. is a rectangular ring made of flat iron, of dimensions equivalent to the cross section of any selected smoke flue. B. 1, are legs of angle iron to 45 sustain ring B., which are attached thereto by screw bolts b, 2, in order to permit adjusting movements; the point of connection of the legs b, 1, is a bent lip b, 3, formed of a division of the legs to give a hinge like 50 motion in their relation with B. and by the angular bend to effect adjustment to the various lateral dimension of fire places, as well as fine adjustment to any case. The feet of legs b, 1, are acutely angular in each 55 direction, as shown in Fig. 1, and Fig. 2; b,

4, is an adjustable tie bar, having perforations to regulate distance between the feet of the legs to agree with the cross dimension of throat A. Fig. 5. Legs b, 1 have like perforations to secure engagement with said 60 bar b, 4, by screw bolts b, 2; b, 5, is an adjustable brace, connected with the distal legs.

The connection of b, 1, with ring B. by means of lip b, 3, and screw bolt b, 2, is 65 shown by Fig. 2, and also the acute angular form of the feet, b, 1; this mode of connection provides adjustment to place ring B. in apposition with the smoke-flue C.

The placement of legs b, 1, seated in re- 70 cess b, 6, with their triangular spread in accordance with the width of the fire place, and their connection with B. in relation with smoke-flue C. is seen by Fig. 4 which also shows that D. 1, is the perpendicular 75 wall of pocket D; end of brace b, 4; plate P. and horizontal line of throat A; Fig. 4 also shows at one side the masonry arrangement to secure smoothness.

Fig. 5, shows the apparatus, (former) 80 placed in line with throat A; the terra cotta flue C. and shows the backward inclination usually required; the hinge like arrangement of lip b, 3, permitting movement to secure adjustment to any position assigned 85 for the smoke flue C; Fig. 5 also shows end view of plate P. made of iron, or of "gal- vanized sheet iron," crimped at each side for rigidity, as laid from leg to leg to support rubble or concrete work, as a base for 90 masonry; the adjustable bar b, 5; the recess b, 6; and exhibits the support of the masonry and the means to secure smooth- ness of the smoke chamber.

Having thus described my invention, 95 what I claim, and desire to secure by Letters Patent is,—

A device of the class described, composed of a rectangular ring with legs attached thereto, in a manner to produce a truncated 100 pyramidal adjustable fixture; the legs of angle iron, having at the upper ends a perforated lip set at an angle therewith to give the fixtures a broad base; said legs being connected with the ring by screw bolts, as 105 shown, to permit adjusting movements; the feet of the legs resting in recesses of the masonry; the base of the legs having acute angular form in both directions on the frontal aspect to approximately coincide 110

with the level of the base on which they rest; in the lateral aspect of the fixture the angle is so acute as to have the fixture resting on four points to permit free movement 5 and to avoid disturbing the levels of the ring in each direction; having a tie bar to adjust the base of the lateral sides to the dimension of the throat A; an adjustable brace attached to the distal legs to define 10 the pocket D, and to control and support the

masonry at that region; all the several parts being formed and connected with each other substantially as described.

In testimony, that I claim the foregoing as my invention, I affix hereto my signature, this twenty sixth day of August A. D. 1911.

LOUIS JACK.
